COMBINED TELEVISION HOUSING AND SUPPORT BRACKET THEREFOR

Walter G. Anders, Canton, Ohio, assignor to Diebold,
Incorporated, Canton, Ohio, a corporation of Ohio

Filed Oct. 9, 1967, Ser. No. 8,918

Term of patent 14 years

Int. Cl. D14—03

U.S. Cl. D56—4

Fig. 1

Fig. 5

Fig. 2

Fig. 3

Fig. 4

FIG. 1 is a perspective view of a combined television housing and support bracket therefor, showing my new design;

FIG. 2 is a top plan view showing the top of the housing and bracket;

FIG. 3 is a front view showing the housing and bracket;

FIG. 4 is a bottom plan view showing the housing and bracket; and

FIG. 5 is a side elevational view showing the side illustrated at the right of FIG. 1.

The dominant features of my design reside in the portions shown in full lines on the drawings.

I claim:

The ornamental design for a combined television housing and support bracket therefor, as shown and described.
